Robert Z. Greene, Norwalk, Conn., Vaul Benson, Newark, N. J., and Raymond Spilman, Bronxville, N. Y., assignors to Rowe Manufacturing Co., Inc., Whippany, N. J., a corporation of New York

Application October 25, 1954, Serial No. 32,820

Term of patent 14 years

(Cl. D52—3)

Figure 1 is a perspective view of a merchandising machine display panel showing our new design, with a merchandising machine in connection with which the display panel is adapted to be used shown in broken lines.

Figure 2 is a plan view of our merchandising machine display panel drawn on an enlarged scale and viewed along the line 2—2 of Figure 1.

Figure 3 is a sectional view of our merchandising machine display panel drawn on an enlarged scale and viewed along the line 3—3 of Figure 1.

The broken line showing of the merchandising machine is for illustrative purposes only and included for clarity of disclosure.

We claim:

The ornamental design for a merchandising machine display panel, substantially as shown and described.
